[57] CLAIM

The ornamental design for a collator for use with copier, as shown and described.

DESCRIPTION

FIG. 1 is a top and right front perspective view of a collator for use with copier showing my new design; FIG. 2 is a bottom and left rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front elevational view thereof with the copied paper receiver moved to the right. The broken-line showing of a copier thereon is environmental and forms no part of the claimed design.
